Primary Examiner — Vy N Koenig

(57) **CLAIM**

The ornamental design for a gimbal, as shown and described.

DESCRIPTION

FIG. 1 is a front elevational view of the gimbal showing our new design;

FIG. 2 is a rear elevational view thereof;

FIG. 3 is a left elevational view thereof;

FIG. 4 is a right side elevational view thereof;

FIG. 5 is a top plan elevational view thereof;

FIG. 6 is a bottom plan view thereof; and,

FIG. 7 is a perspective view thereof.

The broken lines in the drawings depict features of the gimbal that form no part of the claimed design,
